A. WEISSENBORN.

Tuck Marker for Sewing Machines.

No. 3,491.

Reissued June 8, 1869.

United States Patent Office.

ANNA WEISSENBORN, OF NEW YORK, N. Y.

Letters Patent No. 65,141, dated May 28, 1867; reissue No. 3,491, dated June 8, 1869.

IMPROVEMENT IN TUCK-CREASING ATTACHMENT FOR SEWING-MACHINES.

The Schedule referred to in these Letters Patent and making part of the same.

To all whom it may concern:

Be it known that I, ANNA WEISSENBORN, of the city, county, and State of New York, have invented a new and useful Improvement in Tuck-Markers or Creasers; and I do hereby declare that the following is a full and exact description thereof, reference being had to the annexed drawings, making a part of this specification, in which—

Figure 1 represents a top view of my invention.

Figure 2, a side view of the same.

Figures 3 and 4 show a modification of my invention.

Figures 5 and 6 represent a simpler application of my invention, using the spindle of the marking-wheel as a spring.

Figures 7 and 8 show a different form for a bearing of the marking-wheel.

Similar letters of reference indicate corresponding parts in all the figures.

The object of my invention is to construct a tuck-creasing device, which may be attached to a sewing-machine, and enable the operator to crease the cloth, during the process of sewing, for different sizes of hem, or tuck; and to this end,

It consists in a sliding blade, having an upturned edge, that is secured to and moves with a bar, carrying a grooved wheel, that presses directly on the upturned edge.

To enable others skilled in the art to construct tuck-creasers according to my invention, I will proceed to describe the same, with reference to the drawings.

A is a metallic gauge-plate, of suitable shape, and provided with a slot, A⁵, through which the screw that secures it to the sewing-machine is passed.

This plate has upright lugs A⁴, that serve as bearings for a pin, on which the lever A² turns.

A⁶ is a guide and bearing, fast to the lever A², and which serves as a bearing for the spindle A⁷, which is held in position by the set-screw A⁸.

The spindle A⁷ is provided at one end with a groove, A⁹, and the spindle in this groove is flattened at its sides, to fit into a slot in the upturned end A¹⁰ of the sliding blade A¹². This prevents the spindle from turning, and attaches the spindle and blade, so that they slide in either direction together.

A grooved wheel, A¹⁰, is attached to the other end of the spindle, by means of the collar A⁹ and nut A¹¹, so as to turn freely on said spindle.

The sliding blade A¹² moves in a groove made in the under side of the fixed gauge-plate A, and has, on its extreme end, an upturned edge, A¹³, on which the wheel A¹⁰ is pressed down, by means of the spring A¹, which is attached to the lever A², and may be regulated by the set-screw A³.

B is an eccentric, attached to the lever A², for the purpose of raising the wheel A¹⁰, by means of the handle A⁵, during the process of creasing, without operating the spring A¹.

Figs. 3 and 4 show a different arrangement of my invention, having the spring directly attached to the spindle-guide A⁶.

Figs. 5 and 6 show still another mode of construction, by dispensing with the spring and constructing the spindle in such a manner as to serve the purpose of the spring.

Figs. 7 and 8 show a different construction of the spindle-guide.

The operation of creasing is accomplished by passing the cloth between the grooved wheel A¹⁰ and the edge A¹³.

Instead of a grooved wheel, an edged wheel might be substituted, and the end of the sliding blade be turned up into a groove.

What I claim, and wish to secure by Letters Patent, is—

1. The combination, with a stationary gauge-plate A, of the movable blade A¹², having a creasing-edge, A¹³, and the creasing-wheel A¹⁰, or their stated equivalents, when the said blade and wheel are connected together and adjustable in relation to the gauge, substantially as described.

2. In combination with the above, a spring, substantially as described, for pressing the wheel against the edge.

3. In combination with the elements of the first clause, the wheel-elevating devices A⁶ B.

4. The combination, with a stationary gauge-plate and with creasing-mechanism, substantially such as described, connected together and adjustable thereon, of a set-screw, for confining the said creasing-devices in proper position with the gauge.

ANNA WEISSENBORN.
